(57) **CLAIM**

The ornamental design for a connector particularly for use in a wheelchair, as shown and described.

DESCRIPTION

FIG. 1 is a perspective view from front, above and right side of the connector of the present invention;

FIG. 2 is a perspective view from rear, and right side of the connector of the present invention;

FIG. 3 is an elevation of the right side of the connector of the present invention, to which the elevation of the left side corresponds;

FIG. 4 is a front elevation of the connector of the present invention; and,

FIG. 5 is a perspective view of the article in use in a wheelchair, with the broken line showing for illustrative purposes only and forming no part of the claimed design.
